VACUUM HEATING PUMP

Filed Dec. 1, 1930

UNITED STATES PATENT OFFICE

1,988,027

VACUUM HEATING PUMP

William P. Whittington, Indianapolis, Ind., assignor to American Steam Pump Company, a corporation of Michigan

Application December 1, 1930, Serial No. 499,201

11 Claims. (Cl. 103—6)

My invention relates to improvements in apparatus for handling the condensation of steam and hot water heating radiators and for removing the condensation from the radiators of the heating system and returning the same to the boilers.

One of the objects of my invention is to provide an improved apparatus for creating the necessary vacuum on such heating system as to cause the proper circulation through the system.

For the purpose of disclosing my invention I have illustrated one embodiment thereof in the accompanying drawing, in which:

Fig. 1 is a longitudinal section of an apparatus embodying my invention;

Fig. 2 is an end view thereof, and

Fig. 3 is a sectional view on the line 3—3 of Fig. 1.

In the embodiment illustrated, I provide a tank or container 1 which is divided into a water circulating section 2 and a boiler feed chamber 3 by a transversely extending wall 4 extending from the bottom of the tank to a point near the top. Mounted upon the top of this tank is a dome 5 provided with a conduit 6 formed by an inner wall 7 and the outer wall of the dome and a conduit 8 formed by an inner wall 9 and the outer wall of the dome. These conduits merge into a pressure chamber 10 at the top of the dome, which delivers through a pair of throats 11 preferably conical in shape and extending downwardly from the wall 12. This wall forms the top of a center column 13, formed by the walls 14 and the throats 11 discharge into vacuum producing tubes 15 which are similar in construction and each tube next its upper end is provided with a Venturi throat 16. The tubes are preferably formed in sections, each section abruptly enlarging as at 17 and 18 and these tubes deliver into a reversing pot, one side of which is formed by the wall 4 and the other side of which is formed by the wall 19, the bottom of the pot being curved as at 20 and provided with a dividing wall 21. The dome has formed therein two chambers, 45 the surge chamber 22 and the accumulating chamber 23. These chambers are connected by means of an inlet pipe 24 with the heating system, this pipe communicating through the ports 25 and 26 with the two chambers respectively. 50 and between these ports there is provided a check valve 27. The accumulating chamber 23 communicates by means of a pipe 28 with the boiler feed chamber 3, the lower end of this pipe being closed by a check valve 29. A circulation pump 30 receives the circulating water in the

circulating tank 2 and delivers the same through the pipe 31 to the conduit 6. A second pump 32 receives the water from the boiler feed chamber 3 and delivers the same to the boiler.

The pump 32 is of the impeller type having an intake 33 at its center, connected with the boiler feed chamber by the pipe 34. One difficulty with this type of pump is that when air or vapor gets into the impeller chamber the pump will cease to function. By connecting the top of the pump 32 casing which encloses the suction chamber of the pump, through the pipe connection 35 with the accumulating chamber 23 any air or vapor in the pump casing will be drawn, under the vacuum produced in the accumulating chamber, 15 from the pump casing insuring the operation of the pump at all times.

Arranged within the boiler feed chamber 3 is a suitable float 36 adapted to control an electric switch 37 for the purpose of shutting off the current through the motor for the pump 32 when the level of the water in the boiler feed chamber falls below a predetermined point and turning the current on through this motor when the level of the water in the chamber rises above a predetermined level.

A second switch 38 controlled by a diaphragm pressure member 39 controls the circuit through the motor of the pump 30 and this diaphragm motor of the switch 38 is connected to the surge chamber 22.

In operation, the circulating chamber 2 is partially filled with water. When the pump 30 is started it forces the circulating water under pressure into the pressure chamber 10, which water 35 returning through the nozzles 11 picks up the air at the port 40, the air and water continuing through the tubes 15 to the reversing pot where the air is directed to the surface and vented through the vent port 41 in the tube 13 while the 40 circulating water returns to the circulating chamber 2.

The air being drawn from the accumulating chamber 23 causes a reduction in the pressure in this chamber with a resultant flow of air and water of condensation from the heating return through the pipe 24 and the check valve 27. The air rises through the accumulating chamber 23 to the port 40 where it is exhausted through the tubes 15 and the water of condensation accumulates in the chamber 23, during the first "heating up" operation, and overflows with the air through the tubes 15 to the chamber 2, mixing with the circulating water. The excess water passes over the baffle wall 4 to the boiler feed chamber 3. 55

from whence it is delivered by the pump 32 to the boiler.

After the first heating up operation, such water as is drawn from the heating system accumulates in the bottom of the accumulating chamber 23 being held there due to the fact that as long as a vacuum is produced in the accumulating chamber the valve 29 will be held closed by atmospheric pressure.

- 10 When the circulation of the heating system is completed and the pressure reduced to the pre-determined point, the automatic vacuum switch 38 opens the circuit through the motor of the pump 30 thereby stopping the pump and reducing 15 the water pressure in the chamber 10 to zero. Under these circumstances the air flow through the vent 41 is reversed, flowing backward through the tube 13 and the chambers 2 and 3 through the duct 8, past the check valve 42 into the pressure chamber 10 and through the nozzles 11, reversing as it passes from these nozzles and flowing through the port 41 into the accumulating chamber 23 with a resultant increase of pressure in this chamber. The weight of the water in this 25 chamber, with the pressure equalized on both sides of the valve 29, is then sufficient to open the valve 29 and the accumulated condensation in the chamber 23 discharges into the boiler feed chamber 3.
- 30 With the pump stopped the valve 27 closes thereby shutting off communication between the chamber 23 and the chamber 22 and thus maintaining a vacuum in chamber 22. This chamber being in direct communication with the heating 35 system through the pipe 24 and the port 25 thus maintains the vacuum in the system during the time that the pump is idle and receives from the system the water of condensation which accumulates in the system.
- 40 It will be noted that the valve 42 opens toward the chamber 10 so that as long as circulating water is flowing through this chamber the valve will be maintained closed by the water in the pressure chamber. As a result so long as the vacuum 45 producing pump is operated the accumulating chamber is sealed to atmospheric pressure.

As there is considerable heat developed in the condensation chamber 23, I utilize this heat for the purpose of heating the water for the boiler. 50 To this end, I provide a feed water heater 45 provided with a series of reverse pipes 44 which pass through the walls of the dome and into the chamber 23, returning and delivering to the discharge chamber 43 of the heater from whence 55 the heated water may be taken to the boiler or wherever desired.

I claim the following:

1. In an apparatus for producing a vacuum in a steam heating system, the combination with an 60 accumulating chamber adapted for connection with the return line of the heating system, a boiler feed chamber communicating therewith, means for creating a vacuum in said accumulating chamber and means for maintaining the connection between said chambers closed as long as a vacuum is maintained in said accumulating chamber.
2. In an apparatus for producing a vacuum in a steam heating system, the combination with a 70 boiler feed chamber, of an accumulating chamber adapted for connection with the return line of the heating system and connected to said boiler feed chamber and delivering the water from the heating system to said feed chamber, means for producing a vacuum in said accumulating chamber.
- 75

ber to create a vacuum on the return side of the heating system, said vacuum preventing the water in said accumulating chamber from being delivered to said feed chamber as long as it is maintained.

3. In an apparatus for producing a vacuum in a steam heating system, the combination with an accumulating chamber adapted for connection with the return line of the heating system, of a boiler feed chamber communicating therewith, means for creating a vacuum in said accumulating chamber, means for maintaining the communication between said chambers closed as long as a vacuum is maintained in said accumulating chamber and means for admitting atmospheric pressure to the accumulating chamber when the vacuum producing means is stopped.

4. In an apparatus for producing a vacuum in a steam heating system, the combination with a boiler feed chamber, of an accumulating chamber 20 adapted for connection with the return line of the heating system connected to said boiler feed chamber and delivering the water from the heating system to said boiler feed chamber, means for producing a vacuum in said accumulating chamber 25 to create a vacuum on the return side of the heating system, said vacuum preventing the water in said accumulating system from being delivered to said chamber as long as it is maintained and means for admitting atmospheric pressure 30 to the accumulating chamber when said vacuum producing means stops.

5. In an apparatus for producing a vacuum in a steam heating system, the combination with a boiler feed chamber, of an accumulating chamber 35 adapted for connection with the return line of the heating system and connected with said boiler feed chamber, a circulating chamber, a liquid piston pump for creating a vacuum in said accumulating chamber and discharging in said 40 circulating chamber and means for delivering the water from said circulating chamber to said pump.

6. In an apparatus for producing a vacuum in a steam heating system, the combination with a boiler feed chamber, of an accumulating chamber adapted for connection with the return line of the heating system and communicating with said boiler feed chamber, a circulating chamber, a liquid piston pump for creating a vacuum in said 50 accumulating chamber and discharging into said circulating chamber, means for delivering the water from said circulating chamber to said pump and an air vent to said circulating chamber.

7. In an apparatus for producing a vacuum in a steam heating system, the combination with a boiler feed chamber, of an accumulating chamber connected with said boiler feed chamber, a liquid piston pump for creating a vacuum in said accumulating chamber, said vacuum preventing the 60 discharge of water from said accumulating chamber to said boiler feed chamber as long as said means is operating, means for admitting atmospheric pressure to said accumulating chamber maintained closed by the water delivery to said 65 liquid piston pump.

8. In an apparatus for producing a vacuum in a steam heating system, the combination with a boiler feed chamber, of an accumulating chamber adapted for connection with the return line of the heating system, said chambers being in communication with one another, means for producing a vacuum in said accumulating chamber, said vacuum preventing the discharge of water from said chamber into the boiler feed chamber as 75

long as it exists, a pump of the impeller type for removing the water from the boiler feed chamber and delivering the same to the boiler and a communication extending from the casing of said 5 pump to said accumulating chamber.

9. In an apparatus for producing a vacuum in a steam heating system, the combination with a boiler feed chamber, of an accumulating chamber adapted for connection with the return line of 10 the heating system and connected with said boiler feed chamber, a liquid piston pump for creating a vacuum in said accumulating chamber including a discharge nozzle and a piston tube having an air inlet at its upper end communicating with 15 said accumulating chamber, a pressure chamber above said discharge nozzle, an air vent into said pressure chamber and means for maintaining said vent closed by the pressure of water in said pressure chamber.

10. In an apparatus for producing vacuum in a steam heating system, the combination with a

boiler feed chamber, of means for producing a vacuum in the heating system and causing the water of condensation to be delivered to said boiler feed chamber, a pump of the impeller type for removing the water from the boiler feed chamber and delivering the same to the boiler, means connecting the suction chamber of the casing of said pump with said vacuum producing means, said pump having an intake at atmospheric pressure. 5

11. The combination with a suction pump of the impeller type having an intake at atmospheric pressure, of a vacuum-producing means and means for connecting the suction chamber of the pump with said vacuum-producing means 15 to remove during the operation of said pump any gas which may be entrapped in said pump, said connecting means being liquid sealed against gaseous backflow. 10
